Application January 18, 1933, Serial No. 652,313

9 Claims. (Cl. 66—42)

This invention pertains to the art of knitting and relates more particularly to a novel method of and apparatus for knitting single face or plain fabrics, and to certain novel fabrics produced by such apparatus and method. The class of fabrics to which the present invention relates are in general distinguished by a small all-over pattern on the front or right side and by the presence of a multitude of floats of yarn at the back or rear side. In most instances the front of the fabric shows a diaper pattern characterized by the presence of an opening or openings within the boundaries of each figure (resulting from the inclusion of tuck stitches and/or float 5 stitches) and by more or less elevated lines or areas, for example, diagonally extending rows of sinker loops forming the borders of the pattern figures, or tuck stitches containing a multiplicity of yarn bights such as to cause a stitch or 10 stitches to project from the plane of the fabric to form an accent point in the figure. In fabrics of this class the usual needle wales are so distorted as to become substantially unrecognizable, and such ribs as may appear extend diagonally or transversely, rather than lengthwise of 15 the fabrics.

Fabrics of this general class are sufficiently elastic for use in garments; they show a marked tendency to resist runs when a yarn is ruptured; 20 and by reason of their ornamental and often sheer and gauzy effect, they are particularly useful in the manufacture of underwear or other articles in which daintiness or delicacy of appearance is requisite, but are to be distinguished 25 from knitted fabrics in which eyelets or patterns are produced by transferring loops from one needle to another, the fabrics herein disclosed being produced rapidly upon machines of simple type and without recourse to transfer.

Characteristic of fabrics of the class herein described is the fact that in any given wale, groups, each consisting of a plurality of predetermined stitch formations, alternate with groups differently constituted, while in adjoining wales 30 these respective groups are staggered. As herein specifically disclosed the desired effects are obtained by the employment of a plurality of yarns, for example, a body yarn and a facing yarn (although a greater number of component yarns 35 may be employed) at each knitting point, and in the knitting operation both yarns knit in plating relation while forming the stitches constituting one kind of group, but in some at least of the stitches of another kind of group, the facing 40 yarn is floated to the rear of the backing yarn.

In most instances some of the stitches of said second group are tucked and contain bights of two or more yarns and in some instances have a float of another yarn at the rear side. The character and successive arrangement of the 5 stitches of the second group determines the distinctive pattern upon the face of the fabric.

In accordance with the preferred method, knitting simultaneously proceeds at a plurality of knitting points and at each point a plurality 10 of yarns is fed. The needles are so actuated and the yarns are delivered in such relation that in a plurality of successive courses a given needle will knit stitches all of like character, for example, each having two yarns in plating relation, 15 while an adjoining needle, in knitting loops of corresponding courses, knit stitches some at least of which are different from those knit by the first-named needle; for example, these stitches made on the second needle may comprise one 20 yarn floated behind the other. When both needles have thus knitted in the production of a predetermined number of courses, their respective modes of operation are reversed, so that now the second needle knits a succession of stitches 25 identical with those previously made by the first needle, while the latter now knits stitches, some of which at least are different from those which it first knits. Each pair of adjacent needles thus 30 knits first according to one mode and then according to a different mode, the resultant fabric having the characteristics above noted.

Conveniently, and as here illustrated, I employ a multifeed circular knitting machine having an even number of feeds, for example, a machine having eight feeds. At each feed or knitting point, appropriate yarn feed devices and knitting cams are arranged.

Difficulty has heretofore been experienced in 35 knitting float stitches on machines of large diameter (such as a multifeed machine of the kind just referred to) due to the fact that if the facing yarn is given a lead sufficient to wrap about the non-float needles, it does not lie high enough 40 on the needle cheeks to allow it to roll back over the top of the float needle. In accordance with the present invention this difficulty is overcome 45 by causing the non-float needle to clear and rise high enough to take the facing yarn before the float needles are cleared, and by making the lead 50 for the facing yarn just long enough to cause the yarn to wrap about the non-float needles at a point just above the tops of the float needles as the latter now move upwardly to clear. Preferably the heads of the needles are forwardly 55

offset or bent, and the rising of the up-going float needle is so timed as to cause the facing yarn to roll over the back of its head while the float needle completes its upward movement. Then, 5 in descending, all of the needles take the backing yarn.

In the accompanying drawings I have illustrated various fabrics of the class above referred to together with mechanism useful in the production of each of these illustrated fabrics as exemplifying the general class to which these fabrics belong and the proper arrangement of apparatus whereby such fabrics may be produced, but with the understanding that the invention is not narrowly restricted to fabrics or to the production of fabrics specifically like those herein illustrated but relates broadly to a method of and apparatus for producing fabrics of this general class and to certain types of fabric falling within said class.

20 In the drawings,

Fig. 1 is a diagrammatic elevation of a development of one-half of the cam cylinder of a circular knitting machine embodying the present invention;

25 Fig. 1^a is an elevation similar to Fig. 1, showing the diametrically opposite half of the cam cylinder of the same machine;

30 Fig. 1^b is a reproduction of a photomicrograph of the front face of fabric knitted by a machine employing cams arranged as shown in Figs. 1 and 1^a;

35 Fig. 1^c is a diagrammatic view illustrating the kind and sequence of fundamental stitch formations making up a repeat of the fabric of Fig. 1^b, but without attempt to show the variations in loop length due to inclusion in or omission of yarns from certain of the constituent stitch formations;

40 Fig. 1^d is a chart illustrating the kind and sequence of stitch formations employed in the fabric of Fig. 1^b;

45 Figs. 2 and 2^a are views corresponding to Figs. 1 and 1^a, but showing a different arrangement of cams from that of Fig. 1;

50 Fig. 2^b is a reproduction of a photomicrograph of fabric knitted by the use of cams arranged as shown in Figs. 2 and 2^a;

55 Fig. 2^c is a diagrammatic illustration similar to Fig. 1^c, but illustrating the stitch formation resulting from the employment of the cams of Figs. 2 and 2^a;

60 Fig. 2^d is a chart illustrating the sequence of stitch formations in the fabric of Fig. 2^b;

65 Figs. 3 and 3^a are views similar to Figs. 1 and 1^a, but showing a further arrangement of cams;

70 Fig. 3^b is a reproduction of a photomicrograph of the fabric knitted by means of the cam arrangements of Figs. 3 and 3^a;

75 Fig. 3^c is a diagrammatic illustration similar to Fig. 1^c, but showing the stitch arrangement produced by the cams of Figs. 3 and 3^a;

80 Fig. 3^d is a chart illustrating the sequence of stitch formations in the production of the fabric shown in Fig. 3^b;

85 Figs. 4 and 4^a are views similar to Figs. 1 and 1^a, but showing a modified arrangement of cams;

90 Fig. 4^b is a reproduction of a photomicrograph illustrating the rear face of fabric knitted by means of the cams of Figs. 4 and 4^a;

95 Fig. 4^c is a diagrammatic illustration similar to Fig. 1^c, but indicating the fabric produced by the mechanism of Figs. 4 and 4^a;

100 Fig. 4^d is a chart illustrating the stitch formation of the fabric shown in Fig. 4^b;

105 Figs. 5 and 5^a are views corresponding to Figs.

1 and 1^a, but showing a further arrangement of cams;

110 Fig. 5^b is a reproduction of a photomicrograph of the rear face of fabric produced by the mechanism of Figs. 4 and 4^a;

115 Fig. 5^c is a diagrammatic illustration similar to Fig. 1^c, but showing the fabric structure produced by the mechanism of Figs. 5 and 5^a;

120 Fig. 5^d is a chart showing the sequence of stitch formations of Fig. 5^b;

125 Figs. 6 and 6^a are views similar to Figs. 1 and 1^a, showing a still further arrangement of cams;

130 Fig. 6^b is a reproduction of a photomicrograph of fabric produced by the cam arrangements of Figs. 6 and 6^a;

135 Fig. 6^c is a diagrammatic illustration of the fabric of Fig. 6^b;

140 Fig. 6^d is a chart showing the stitch distribution in the fabric of Fig. 6^b;

145 Figs. 7 and 7^a are views similar to Figs. 1 and 1^a, illustrating another cam arrangement;

150 Fig. 7^b is a reproduction of a photomicrograph of fabric produced by the cams of Figs. 7 and 7^a;

155 Fig. 7^c is a diagrammatic illustration of the fabric of Fig. 7^b;

160 Fig. 7^d is a chart indicating the stitch formation of Fig. 7^b;

165 Fig. 8 is a diagram, in perspective, illustrating the successive elevations of the needles of two sets at a given feed point and the manner of delivering a facing and a body yarn respectively to the needles;

170 Fig. 9 is a vertical section illustrating a pair of needles so positioned as to permit a yarn fed to one needle to pass behind the latter as said needle rises;

175 Fig. 10 is a radial section illustrating the general arrangement of needle carrier and cam carrier in a machine of the class herein disclosed; and

180 Figs. 1^x, 2^x, 3^x, 4^x, 5^x, 6^x and 7^x are reproductions, to enlarged scale, of photographs of the several fabrics herein described.

185 By the present invention I provide for the knitting of a variety of fabrics all belonging to the same genus and distinguished from other fabrics, but having unlike groups of stitch formations alternating in each wale, the like groups in adjacent wales being staggered.

190 In the patent to Smith No. 1,772,230, dated August 5, 1930, there is disclosed one fabric belonging to the general class to which the present invention relates. In said patent the fabric disclosed is described as knitted upon a single feed

195 hosiery machine by the employment of needle controlling pattern means of complex type, and as therein disclosed the same pair of yarns is concerned course after course in the knitting of the fabric. In accordance with the present invention I provide means whereby fabric having the same general stitch formations as that disclosed in the patent to Smith, for example, may be knit expeditiously and at high speed by

200 the use of simple knitting instrumentalities without resort to complicated pattern mechanism and with possibility for further ornamentation by means of color change or the like which can only be attained with difficulty, if at all, by the use of the method and apparatus disclosed in said patent to Smith.

205 In the patent to Smith a single species of fabric is disclosed, such fabric being referred to as diagonal network and being commonly known in the trade as "diamond mesh" fabric. This fabric, as is common to fabrics of the general

class to which it belongs, is a one-face or plain fabric and is distinguished by capacity to stretch in either dimension of the fabric with concomitant contraction in the other direction.

5 In accordance with the present invention, fabric having the general appearance of that disclosed in the Smith patent, but structurally differing therefrom in that in the new fabric successive courses are not made from the same pair 10 of yarns, may be produced upon a multifeed circular machine having a cam arrangement such as shown in Figs. 1 and 1^a.

The machine employed may be of a type in which either the needle carrier or the cam carrier moves, but is here shown as a circular independent latch-needle machine in which the bed 1 of the machine (Fig. 10) is stationary and supports the stationary needle carrier or cylinder 2 having the usual vertical slots 3 for the 20 reception of vertically sliding needles. The series of needles is divided into two sets, distinguished by long and short butts 6 and 7 (Fig. 9), respectively. As here illustrated, the needles of one set alternate with those of the other set, 25 but other groupings of the long and short butt needles may obviously be employed, if desired, for example, groups each containing two or more long butts, alternating with groups each containing two or more short butts. The bed plate 30 1 of the machine is provided with bearings for the rotating gear ring 8 upon which are removably mounted segmental blocks 9 to which the several sets of knitting cams, respectively, are secured. These segmental blocks 9 are removably secured to the ring 8 as by means of bolts 10, and preferably these blocks are of uniform 35 and like dimensions so that any one block may be substituted for another. As here shown the machine is provided with the usual sinker bed 11 and sinkers which cooperate with the needles at the verge 12 of the cylinder to form the 40 stitches.

The machine herein disclosed by way of illustration is a machine of large diameter such as 45 is commonly employed for knitting underwear, and is provided with eight feed points and corresponding sets of needle actuating cams, and at each feed point provision is made for delivering at least two yarns *x* and *y* respectively. Two 50 yarn guides M and N at one of the feeds are shown in Fig. 8 of the drawings. For convenience in description, I shall hereinafter employ the term "stitch formation" as inclusive of all such yarn arrangements as plain knitted loops, 55 tuck loops, floats, dropstitches, etc., whether comprising a single yarn or a plurality of yarns, produced by the action of a given needle in performing its intended sequence of operations.

Referring to Figs. 1 and 1^a, the cam arrangement for making a diamond mesh fabric, similar in stitch formation to that shown in the above-named patent to Smith, comprises eight sets of cams A, B, C, D, E, F, G and H respectively, each set of cams being mounted as above described on one of the segmental blocks 9. The cam set A, for example, comprises a stitch cam 14 and preferably a bottom cam 15 designed to limit down-throw of the needles. The cam set also preferably includes the upper and lower 65 cams 16 and 17, providing between them a needle groove into which the butts of all of the needles pass after leaving the stitch cam 14.

Preceding the stitch cam are two needle lifting cams 18 and 19 respectively, the cam 18 being in advance of the cam 19. The cam 18 is fur-

nished with a needle depressing ledge 20 of a thickness such as to engage the long butt needles but not to engage the short butt needles. This cam ledge 20 thus causes long butt needles which come in the field of action of this 5 cam set to move downwardly into the groove 21, while short butt needles are elevated by cam 18 to the clearing level and delivered into the groove 22. The cam 19 has a clearing portion 23, located at a point between the cam 18 and the 10 cam 14, which is adapted to raise the long butt needles to substantially the same high level as the elevated short butt needles.

Referring again to Fig. 8, the yarn feed guide M delivers the facing yarn *x* at a point with just 15 sufficient lead to wrap it about the non-float needles (which, at the cam set A, are the short butt needles 6) above the needle cheeks and below the needle hooks but above the tops of the float needles (the long butt needles 7 at cam set A) 20 which are just beginning to rise along the slope of the cam 23. The facing yarn *x* as delivered by the guide M wraps around the non-float needles so as to be taken with certainty by the hooks of the latter, but as the float needles rise along the 25 slope of cam 23, their tops come up in front of the yarn *x* (this action being made more certain by a forward offset or bending of the needle hooks, as shown in Fig. 9) so that the float needles fail to receive the yarn *x* which drops down 30 behind these needles.

The body yarn *y* is fed from the guide N, but at such a point that it wraps around both sets of needles after the float needles have been elevated by the cam 23. Thus the yarn *y* is taken in the 35 hooks of both sets of needles. As the non-float needles already have been fed with yarn *x*, the depression of these needles by the cam 14 causes the yarns *x* or *y* to be drawn into stitches in which the two yarns are disposed in plating relation, 40 while, on the other hand, the float needles, which have received the yarn *y* only, knit single loop stitches from this yarn while floating yarn *x* at the back.

At this point it may be noted that while but two 45 guides M and N are illustrated, other guides and other yarns may be employed, as is obvious to those skilled in the art, either in substitution for the yarns *x* and *y* or, in some cases, in addition thereto.

After passing the cams 14 and 15, the needles of both sets rise into the groove defined by the cams 16 and 17 and are eventually delivered to the next cam set B for actuation by the latter. As shown in Fig. 1, the cam sets A, B, C and D 55 are substantially identical, except that the cam 17 of the set D is cut away at 24 to permit delivery of the needle butts at a level for proper engagement with the cam 25 of the next set E, it being understood that the set E follows directly 60 in sequence after the cam set D. As shown in Fig. 1^a, the cam set E comprises a stitch cam 14 similar to the stitch cams of the preceding sets, but instead of the cams 18 and 19 of the preceding sets, the set E is furnished with a cam 25 having a cam slope 25^a adapted to raise the long butt needles into the groove 26, at which point they are cleared. This cam 25 also has a cut-away 65 portion 27 provided with a cam slope 27^a adapted to raise the short butt needles to the clearing 70 position at a point subsequent to that at which the long butt needles are cleared. At this cam set E the yarns are fed in substantially the same way as at the cam sets previously referred to, but since the long and short butt needles are raised in 75

reverse order to that at which they were elevated by the preceding cam sets, the needles which previously floated the yarn *x* now take the latter in their hooks, while those which took both yarns 5 *x* and *y* now float yarn *x*.

The cam sets F, G and H are identical with the cam set E, except that whereas the cam 17 of the set E is cut away at 24, the cam 17 of the set H has a riser 28 adapted to deliver the needles at 10 the proper elevation for engagement by the cam slope 20 of the cam 18 of set A.

While but two series of cam sets A, B, C, D and E, F, G, H are here illustrated as collectively taking up the entire circumference of the cam 15 cylinder, it is to be understood that in machines of greater diameter, these two series might be repeated as many times as space would permit.

Referring to Fig. 1^c, the fabric resulting from the employment of the cams of Figs. 1 and 1^a is 20 indicated diagrammatically but without reference to the actual effects produced due to the shift in adjacent needle wales from one stitch formation to another and the consequent distortion of normal needle and sinker loops. In this 25 figure the needle wales knitted upon low and high butt needles respectively are designated at the upper part of the view by the letters L and H and the intervening sinker wales by the letter Z. The facing and body yarns are designated *x* and 30 *y* respectively, and the courses knitted at the cam sets A, B, etc., are indicated by the letters *a*, *b*, etc. Thus, referring to the left-hand needle wale produced on the low butt needles L, the 35 stitch formation in course *a* includes both yarns *x* and *y* in plating relation. This is also true in courses *b*, *c* and *d*. On the other hand, in the corresponding courses in the next needle wale knitted on the high butt needles, each of the 40 stitch formations comprises a single knitted loop of the yarn *y* with the yarn *x* floating at the rear of the fabric. At the course *e* the low butt needle knits a single loop of the yarn *y* while floating the yarn *x*, and the same stitch formation is produced in the succeeding courses *f*, *g* and *h*, while 45 in the corresponding courses of the next adjacent wale knitted on the high butt needles each needle knits both yarns in plating relation.

The resulting fabric, as actually formed by the machine, has the general appearance indicated 50 in Fig. 1^x, which is a reproduction of an enlarged photograph of the fabric, while its actual structure is shown in Fig. 1^b. Since both yarns employed in forming the fabric illustrated were of like material (rayon) and of the same color and 55 twist, the plated arrangement can not well be distinguished in the fabric as produced, but the diagonal arrangement of the raised sinker wales *z* is readily noticeable in Fig. 1^x. In the patent to Smith, above referred to, the reason for the 60 production of these diagonally extending sinker wales is fully discussed and need not be repeated here, it being sufficient to refer to the statement made therein that the results attained occur when, in knitting loops from yarns knit in plated 65 relation systematically alternated with a single yarn knit in a flanking wale of the same course, any mode of knitting is resorted to which will be competent to produce a relatively unyielding structure at the initiation of a wale of loops in 70 one only of the component yarns; for example, when the alternated relationship between a wale knit by a needle taking both yarns and the wale knit by a needle taking only one is regularly reversed after a certain plurality of courses so that the needle which took both yarns then

takes one only, and the needle which took the single yarn thereafter takes both.

While in the patent one mode and mechanism useful in providing one specific example of this genus of fabrics is disclosed, said patent indicates 5 only that method and that fabric which results from the employment of a single yarn feed with appropriately arranged needle selecting pattern devices. In the present arrangement the resulting fabric, as above pointed out, differs from 10 that of the Smith patent in that the same pair of yarns recurs only once in eight successive courses. Thus, if it be desired, highly ornamental results may be attained by the use of differently colored yarns at successive yarn feeds or by the 15 use of yarns of different materials or different twist.

Fig. 1^d is a chart such as may be used by the knitter in setting up the cam arrangements of 20 Figs. 1 and 1^a in order that he may attain the results above described.

While the simple diamond mesh fabric above referred to is representative of the class of fabrics to which the present invention relates and has been found highly useful, for example, for 25 hosiery knitting, I have now discovered that other fabrics belonging to the same general class but differing markedly from the fabric of Fig. 1^b may be produced in a manner similar to the fabric of Fig. 1^b but by slightly different arrangements of the cam sets of the machine. 30

Thus, as shown in Figs. 2 and 2^a, the cam sets A to H correspond in general to those of Figs. 1 and 1^a. In fact, the cam sets A, B and C may be identical with the cam sets A, B and C of Fig. 1, 35 while the cam sets E, F and G of Fig. 2^a are identical with the corresponding sets of Fig. 1^a. However, the cam sets D and H of Figs. 2 and 2^a differ from the cam sets D and H of Figs. 1 and 1^a in that their cams 19 and 25, respectively, are cut 40 away at 23^a and 28^a, respectively, so that needles elevated by these cams only reach the tuck point. Thus in passing the cam 19 of set D the long butt needles do not rise high enough to clear their 45 stitches, and thus they form tucks of the backing yarn and also float the facing yarn. Likewise the short butt needles in passing the cam 25 fail to clear their stitches and so form tucks of the 50 backing yarn and also float the facing yarn.

Referring to Fig. 2^c, the resulting fabric is 55 diagrammatically illustrated. In course *a* (knitted on cam set A) the low butt needle (tucked in passing the preceding cam set H) holds a loop of the backing yarn *y* of the preceding course *h*, and at the cam set A takes and knits both the yarns *x* and *y* delivered at this feed point. In the following courses *b*, *c* and *d* (knitted at the cam sets B, C and D) the low butt needles take both yarns and knit. In the courses 60 *a*, *b* and *c* the high butt needles knit stitches from the yarn *y* only while floating the yarn *x* at the back. However, at the cam set D, the high butt needles tuck the backing yarn *y* while 65 floating the facing yarn *x*. The general appearance of the resulting fabric is shown in Fig. 2^x, while its actual structure as produced by the machine is illustrated in Fig. 2^b. In Fig. 2^x it will be noted that the tuck stitch at *o* produces 70 an opening of substantial size in the fabric, while the sinker wales *z* are thrown into prominence and set off the fabric into geometric patterns, each including one of the tuck stitch openings within its borders.

Fig. 2^d is a chart to assist the knitter in setting up the cam sequence shown in Figs. 2 and 2^a. Figs. 3 and 3^a illustrate another arrangement for knitting a further form of this class of fabrics. In Figs. 3 and 3^a the cam sets are identical with the cam sets of Figs. 2 and 2^a but whereas the yarns *x* and *y* are fed at spaced points, as shown in Fig. 8, at all of the feeds of Figs. 2 and 2^a, they are thus fed only at cam sets A, B, C, E, F and G of Figs. 3 and 3^a, but at the cam sets D and H, both yarns are delivered at the same point and so that both yarns are taken by all of the needles. The resultant fabric is diagrammatically illustrated in Fig. 3^c. The left-hand wale is produced by a short butt needle and in course *a* this needle, which carries both yarns of the previous course *h* in the form of a tuck loop, now takes both yarns *x* and *y* and casts off a tuck stitch comprising four yarns. In the subsequent courses *b*, *c* and *d* this needle takes the yarns *x* and *y* and knits stitches with the two yarns in plating relation. In the next adjacent needle wale, in courses *a*, *b* and *c* the long butt needle knits the yarn *y* while the yarn *x* is floated at the rear. In course *d* both yarns *x* and *y* are taken by the long butt needle but are retained as a duplex tuck loop, which is afterward cast off as a quadruple tuck stitch *p* in course *e* upon the yarns *x* and *y* delivered at the corresponding feed.

The general appearance of resulting fabric is indicated in Fig. 3^x and its actual structure in Fig. 3^b. This fabric is characterized, not only by the diagonal outstanding sinker wales *z* forming more or less lozenge shape figures, but by very pronounced, knot-like projections *u* (Fig. 3^b) at the intersections of these lozenge-shaped figures, such projections being produced by the four-ply loops of the tuck stitches. A chart for assisting the knitter in setting up this cam arrangement is shown in Fig. 3^d.

Figs. 4 and 4^a illustrate a further cam arrangement for producing another fabric of the genus. In this cam set-up the cams of the sets A and C are substantially alike and arranged to cause the high butt needles to float and the low butt needles to knit both yarns at each feed. On the other hand, the cams 19 of the sets B and D are cut away at 23^a so as to cause the long butt needles 50 to tuck at these points and thus to form tuck loops of both yarns. In the same way the cams of sets E and G are arranged to form floats on the short butt needles and to knit both yarns on the long butt needles, while the cams of sets F and H are arranged to knit both yarns on the long butt needles and to tuck the body yarn and float the facing yarn on the short butt needles. At cam sets A, C, E, F, G and H, the two yarns *x* and *y* are delivered in spaced relation as in Fig. 8, while at cam sets B and D both yarns are delivered together so as to be taken and knit by both sets of needles. The fabric construction is illustrated diagrammatically in Fig. 4^c wherein, in the left-hand wale produced by the short butt needles, the needle which has tucked the body yarn *y* and floated the yarn *x* in passing the cam set H, takes and knits the body yarn and the facing yarn (at cam set A in course *a*) with the previously tucked single loop of the body yarn. In courses *b*, *c* and *d* the same needle takes and knits both yarns in plating relation. In the adjacent wale (knitted by the high butt needle) the body yarn *y* is knit in course *a* while the facing yarn *x* floats. In course *b* both yarns are taken by the needle and held as tuck loops. In course

c the long butt needle takes the body yarn *y*, which is combined with the withheld loops of course *b* to form a triple tuck stitch *n*, and floats the backing yarn *x*. In course *d* both yarns *x* and *y* are tucked and at the next course cast off 5 to form quadruplex tuck stitches *m*.

The general appearance of the fabric is shown in Fig. 4^x while the structure at the back side of the fabric is illustrated in Fig. 4^b, which clearly indicates the multiplicity of floats *l* which substantially cover the entire back. In this fabric, as in the preceding fabrics, the sinker wales at the front of the material are prominent, while the occurrence of pairs of multiple tuck loops in succession gives the appearance of transverse 15 ribs. Fig. 4^d is a chart to assist in setting up the cam arrangement of Fig. 4.

Referring to Figs. 5 and 5^a, an arrangement of cams is disclosed substantially identical with that of Figs. 4 and 4^a, but in this arrangement the 20 yarns are delivered at the cam sets B, D, F and H at a single feed point such that both yarns are always taken by the needles of both sets, whereas at the feeds A, C, E and G the yarns are fed at spaced points, as illustrated in Fig. 8, so that 25 while the facing yarn is floated behind one set of needles, both yarns are taken and knitted by the other set.

In Fig. 5^c this fabric is diagrammatically illustrated, it being noted that in the left-hand wale 30 (formed on the short butt needles) the needle, in approaching the cam set A, carries both yarns in a tuck loop received from the preceding cam set H, which is knit off with a pair of loops received at cam set A to form a quadruplex tuck 35 stitch. In this wale, in courses *b*, *c* and *d*, both yarns are taken and knitted. In the corresponding course *a* of the adjacent wale (knitted on the long butt needle) the yarn *y* is taken and knitted while the yarn *x* is floated. In course *b* both 40 yarns are taken and held as a tuck loop which is knitted off in course *c* with the single yarn *y*, while the yarn *x* is floated. In course *d* both yarns are taken but retained as a tuck loop, which is knitted off as a quadruplex tuck stitch *m* in 45 the next course *e*. The general appearance of this fabric is shown in Fig. 5^x, while the structure at the back of the fabric is shown in Fig. 5^b, the prominence of the floats being clearly indicated. In this fabric, as in the others of the class, the 50 sinker wales are prominent at the front face, but in this instance the quadruplex tuck stitches *m* (Fig. 5^c) following the triple tuck stitches *n* produce pronounced forward projections on the face of the fabric, the quadruplex stitch being 55 more pronounced than the triple stitch. These quadruplex stitches form accent points defining the corners of polygonal-shaped figures, and at substantially the center of each figure there is an opening *t* (Fig. 5^x) resulting from the stretching 60 of the single yarn loop *k* (Fig. 5^c) lying immediately below the triple tuck stitch. Fig. 5^d is a diagram to assist in setting up the cam arrangement of Figs. 5 and 5^a.

Figs. 6 and 6^a not only show the cam arrangement for a further species of fabric, but also show the yarn feeds and the paths of the needles in taking the yarns. In these figures the cam sets A, C, E and G are substantially identical with those of Fig. 1, while in cam sets B, D, and F, H 70 arrangement is made for tucking the long and short butt needles, respectively. In accordance with the arrangement shown in these figures, the body and facing yarns are fed in spaced relation at cam sets A, C, D, E, G and H, but both the 75

backing facing yarns are fed at the same feed point at cam sets B and F. Thus, while at the cam sets A and C the short butt needles take and knit both yarns and the long butt needles float the facing yarn, at cam set B the short butt needles take and knit both yarns while the long butt needles tuck both yarns, and at cam set D the short butt needles take and knit both yarns while the long butt needles float the facing yarn and tuck the backing yarn. Likewise at cam sets E and G the long butt needles take and knit both yarns and the short butt needles float the facing yarn, while at cam set F the long butt needles take and knit both yarns and the short butt needles tuck both yarns, and at cam set H the long butt needles take and knit both yarns while the short butt needles float the facing yarn and tuck the backing yarn.

This fabric is diagrammatically illustrated in Fig. 6^c. In this figure the short butt needle, in making the left-hand wale, carries a single tucked loop of the backing yarn, from the preceding course, which is cast off with loops of the backing and facing yarn to form a stitch in course a. In courses b, c and d both yarns are taken and knitted. In course a of the adjacent wale (knitted by the long butt needle) a single loop y of the backing yarn is knitted while the yarn x floats. In course b both yarns x and y are taken and held as a tuck loop which is cast off with a single loop y of the backing yarn in course c to form a triple tuck stitch n while the corresponding yarn x floats. In course d this needle takes and holds a loop of the backing yarn y to form a tuck stitch, while the yarn x floats, and this tucked loop y is cast off in the subsequent course e with loops of the yarns y and x delivered at the cam set E to form a triple tuck stitch m.

The general appearance of the fabric is shown in Fig. 6^a, while the structure at the rear side is shown in Fig. 6^b, the large number of float stitches being clearly indicated. The front of this fabric exhibits the appearance of transverse ribs with diagonal series of depressions, the ribs being produced by projections formed by the pairs of successive tuck stitches, n, m, indicated in Fig. 6^c. In this case both tuck stitches contain triple loops, the tuck stitch m being thrown out into prominence while the single loop k below the tuck stitch n is stretched to form an opening q (Fig. 6^a). Fig. 6^d is a diagrammatic chart to assist in setting up the machine for this fabric.

Figs. 7 and 7^a illustrate a further arrangement of cams. In Fig. 7 the cam arrangement is substantially identical with that shown in Fig. 4, for example, while the cam arrangement shown in Fig. 7^a is substantially like that shown in Fig. 6^a.

However, the yarn feed at cam sections A and C is substantially such as shown in Fig. 8, the two yarns x and y being delivered at spaced points, while at cam sections B and D both yarns are also fed at spaced points. At cam sections E and G the yarns are fed at spaced points as in the corresponding sections in Fig. 1^a, and at cam sections F and H the yarns are likewise fed at spaced points.

The resulting fabric is illustrated diagrammatically in Fig. 7^c. The left-hand wale is produced by the short butt needle. In course a this needle carries a single tucked loop of the body yarn y of the preceding course and casts this off with loops of the facing yarn and backing yarn to form a triple tuck stitch. In the succeeding

courses b, c and d this needle likewise takes and casts off both yarns in plating relation. In the corresponding course a of the next needle wale, the high butt needle takes the yarn y but floats the yarn x, while in the next course it takes the yarn y as a tuck loop and floats the yarn x. This tuck loop is cast off in the next course c with another bight of the yarn y to form the duplex tuck stitch n, while another float of the yarn x is formed. In course d this needle takes and holds a tuck loop of the body yarn y and floats the yarn x. In course e this needle takes both yarns and casts them off with loop y of the preceding course to form a triple tuck m. In course f this needle takes both yarns and casts them off, and in the subsequent courses g and h this needle takes both yarns and casts them off as knitted stitches.

The general appearance of this fabric is shown in Fig. 7^a, while its structure is illustrated in Fig. 7^b. Here again the sinker wales form diagonals, while the successive duplex and triple tuck stitches form prominent projections at the face of the fabric, the single loop stitches k (Fig. 7^c) occurring immediately before the first tuck stitch n of a pair, being stretched widely so as to form an opening q (Fig. 7^a) in the fabric. Fig. 7^d is a chart to assist in setting up the cam structure of Figs. 7 and 7^a.

Since the fabric is knitted by the simultaneous action of a plurality of cam sets and corresponding feeds, it can be produced very rapidly, but without recourse to pattern mechanism, needle selecting jacks, or other complicated devices of the prior art. Moreover, as above noted, only two types of cam sets are employed in each series, and these sets may be interchangeably disposed in any desired sequence to produce the effects described. However, as noted, all of the resultant fabrics have a common characteristic distinctive of the genus to which they belong, it being understood, however, that the number of stitch formations in the alternating groups of any given wale may be varied at will.

I claim:

1. That method of making fabric of the class described which comprises as steps dividing a series of knitting needles into two sets, the needles of one set alternating with those of the other, causing the entire series to move relatively to a plurality of successive yarn feeds, delivering two yarns at each feed, causing the needles of one set always to take and knit both yarns at a plurality of such successive feeds while causing some at least of the needles of the second set always to take and knit but one of the yarns at certain of said feeds and others of said second set to form tuck loops at certain of said feeds, and thereafter causing the second set of needles to knit both yarns at each of a plurality of such successive feeds while causing certain needles of the first set to take and knit but one of the yarns delivered at certain of said latter feeds and causing others of said first set of needles to form tuck loops at certain of said latter feeds.

2. That method of making fabric of the class described which comprises as steps dividing a series of knitting needles into two sets, the needles of one set alternating with those of the other, causing the entire series to move relatively to a plurality of successive yarn feeds, delivering two yarns at each feed, causing the needles of one set always to take and knit both yarns at a plurality of such successive feeds while causing some, at least, of the needles of the second set always

to take but one of the yarns delivered at certain of said feeds and to form tuck loops from said one yarn while floating the other yarn at the rear, and thereafter causing all of the needles 5 of the second set to take and knit both yarns in plating relation at each of a plurality of such successive feeds while causing certain needles, at least, of the first set to take but one of the yarns delivered at certain at least of said latter feeds 10 and to form tuck loops from said one yarn while floating the other yarn at the rear.

3. That method of making fabric of the class described which comprises as steps dividing a series of knitting needles into two sets, the needles of one set alternating with those of the other set, causing the series to move relatively to a succession of yarn feeds, delivering a pair of yarns at each of said feeds, causing the needles of one set always to take and knit both yarns at 15 each of a series of said feeds while causing the needles of said second set always to take and tuck one yarn of a pair while floating the other yarn of a pair at each of certain at least of said feeds, and subsequent to the initiation of a number of 20 courses, equaling the number of feeds in said series, causing the needles of the second set always to take and knit both yarns at each of another series of said feeds while causing the needles of the first set always to take and tuck one 25 yarn of a pair while floating the other yarn of a pair at each of certain at least of said latter feeds.

4. That method of making fabric of the class described which comprises as steps dividing a series of knitting needles into two sets, the needles of one set alternating with those of the other set, causing the series to move relatively to a succession of yarn feeds, delivering a pair of yarns at each of said feeds, causing the needles of 30 one set always to take and knit both yarns at each of a series of said feeds while causing the needles of the second set always to take and knit one yarn of a pair at certain of said series of feeds while floating the other yarn at the back, and at another of said feeds causing the needles of 35 said second set always to take and tuck one yarn of a pair and to float the other yarn at the back, and, subsequent to the initiation of a number of courses equaling the number of feeds 40 in said series, causing the needles of the second set always to take and knit both yarns at each of a series of said feeds while causing the needles of the first set to take and tuck one yarn and to 45 float the other yarn of a pair at certain of said latter feeds.

5. A knitting machine of the class described comprising a needle carrier, needles therein, alternate needles being of different kinds, two series of yarn feeds each having means for delivering a pair of yarns and two corresponding series of cam sets, means for moving the needle carrier relatively to the yarn feeds, one set of needle actuating cams being adjacent to each 50 yarn feed, each cam set of each series containing a needle lifting cam, the lifting cams of one series always cooperating with needles of one kind only and the lifting cams of the following series always cooperating with needles of the second kind only, each set of cams of the first series comprising a second cam arranged to actuate needles of the second kind subsequent to the actuation of needles by said first cams, and each set of 55 cams of the next series comprising a second cam arranged to actuate needles of the first kind subsequent to the actuation of needles by the first cam 60 of the set, said second cams being clearing cams in certain sets of each series and being tucking cams in other sets of each series, the feeds corresponding to those sets of cams wherein the second cam is a clearing cam being arranged to 65 deliver one yarn with a greater lead than the other.

cam of the set, said second cams being clearing cams in certain sets of each series and being tucking cams in other sets of each series.

6. A circular knitting machine comprising a needle carrier, needles therein, alternate needles having long and short butts respectively, eight yarn feeds each having means for delivering a pair of yarns, means for moving the needle carrier relatively to the yarn feeds, and a set of needle actuating cams adjacent to each feed, each 10 cam set comprising a needle clearing cam, the clearing cams of four successive sets always co-operating with the short butt needles only, and the clearing cams of the four following sets always cooperating with the long butt needles only, 15 each of the first four sets of cams also including a second cam cooperable with the long butt needles subsequent to the action of the clearing cam, and each of the following four sets of cams including a second cam cooperable with the short 20 butt needles subsequent to the action of the clearing cam, the second cam of certain sets being a tucking cam and the second cam of other sets being a clearing cam, the several sets of cams being interchangeable with one another. 25

7. A knitting machine of the class described comprising a needle carrier, needles therein, alternate needles being of different kinds, two series of yarn feeds each having means for delivering a pair of yarns and two corresponding series of 30 cam sets, means for moving the needle carrier relatively to the yarn feeds, one set of needle actuating cams being adjacent to each yarn feed, each cam set of each series containing a needle clearing cam, the clearing cams of one series always co-operating with needles of one kind only and the clearing cams of the following series always cooperating with needles of the second kind only, each set of cams of the first series comprising a second cam arranged to actuate needles 35 of the second kind subsequent to the actuation of needles by said first cams, and each set of cams of the next series comprising a second cam arranged to actuate needles of the first kind subsequent to the actuation of needles by the first cam 40 of the set, said second cams being clearing cams in certain sets of each series and being tucking cams in other sets of each series, the feeds corresponding to those sets of cams wherein the second cam is a clearing cam being arranged to 45 deliver one yarn with a greater lead than the other.

8. A circular knitting machine comprising a needle carrier, needles therein, alternate needles having long and short butts respectively, eight 50 yarn feeds each having means for delivering a pair of yarns, means for moving the needle carrier relatively to the yarn feeds, and a set of needle actuating cams adjacent to each feed, each set of cams comprising a needle clearing cam, the clearing cams of four successive sets always co-operating with the short butt needles only, and the clearing cams of the four following sets always cooperating with the long butt needles only, 55 each of the first four sets of cams also including a second cam cooperable with the long butt needles subsequent to the action of the clearing cam, and each of the following four sets of cams including a second cam cooperable with the short 60 butt needles subsequent to the action of the clearing cam, the second cams of certain sets at least being tucking cams, the yarn feed means corresponding to certain at least of the cam sets which have the tucking cams being arranged to deliver the two yarns with different leads whereby 65

said feeds the needles of one set take and tuck one yarn while floating the other yarn.

9. A knitting machine of the class described comprising a needle carrier, needles therein, alternate needles being of different kinds, two series of yarn feeds each having means for delivering a pair of yarns and two corresponding series of cam sets, means for moving the needle carrier relatively to the yarn feeds, and one set of needle actuating cams being adjacent to each yarn feed, each cam set of each series containing a normally fixed needle clearing cam, the clearing cam of one series always cooperating with needles of one kind only and the clearing cams of the follow-

ing series always cooperating with needles of the second kind only, each set of cams of the first series comprising a second normally fixed cam arranged to actuate needles of the second kind subsequent to the actuation of needles by said first cams, and each set of cams of the next series comprising a second normally fixed cam arranged to actuate needles of the first kind subsequent to the actuation of needles by the first cam of the set, said second cams being clearing cams in successive sets of each series with a tucking cam in a following set of each series. 5 10

LAURENCE B. HOLT.
